A WALL MOUNTED FOLDABLE SUPPORT FOR AN X-RAY UNIT

Cornelius Keith Vandervelden, Arlington Heights, and
Theodore Prisland, Evanston, Ill., assignors to Litton
Medical Products, Inc., Des Plaines, Ill., a corporation
of Delaware

Filed Mar. 28, 1969, Ser. No. 16,514

Term of patent 14 years

Int. Cl. D24—02

U.S. Cl. D83—1

Fig. 1

FIGURE 1 is a perspective view of a wall mounted foldable support for an X-ray unit showing my new design;

FIGURE 2 is a side elevation thereof;

FIGURE 3 is a front elevation thereof;

FIGURE 4 is a top plan view thereof; and

FIGURE 5 is a rear elevation thereof.

We claim:

The ornamental design for a wall mounted foldable support for an X-ray unit, as shown.
